UNITED STATES PATENT OFFICE

MARION MALLORY, OF TOLEDO, OHIO

CARBURETOR

Application filed November 4, 1929. Serial No. 404,577.

My invention has for its object to provide a means for automatically regulating the manifold resistance of internal combustion engines, whereby the same proportion of gasoline and air may be maintained at all speeds of the engine. This enables a permanent setting of the ignition timing at an advance point to produce the most efficient operation of the invention at any and all speeds.

As is well known in the art, engines that are particularly designed for high speed and which are referred to as high speed engines, require large manifolds and large valves with the result that knocking is invariably produced in such engines when running at low speed, because of the large cross-sectional area of the intake or the low manifold resistance. In internal combustion engines, generally, such as used in connection with automobiles, trucks and the like, when running slowly, the manifolds will deliver, upon opening the throttle, too much air and gasoline, which raises the compression and produces knocking. This may be offset by carburetor adjustment for a definite speed, which produces a too rarefied mixture or too rich a mixture at other speeds. By my invention, the vacuous condition that draws the gasoline from the carburetor outlet, or nozzle, is regulated and the resistance to the air movement into the carburetor is correspondingly regulated, whereby the controlled fuel mixture is introduced into the engine at regulated rate with the result that undue rise in compression is prevented. The speed thus builds up more directly in accordance to the supply of the fuel and the quantity of the fuel mixture is regulated by the speed of the engine with the result that overcharging is entirely eliminated.

The invention may be contained in constructions of different forms and, to illustrate a practical application of the invention, I have selected a means for controlling the fuel mixture, that is dependent for its action on the speed of the engine, as an example of such construction, and shall describe it hereinafter. The structure elected is shown in the accompanying drawings.

Fig. 1 is a longitudinal section through a

carburetor to which my invention is applied. Fig. 2 illustrates a means for actuating parts of the carburetor shown in Fig. 1, according to the speed of the engine to which the carburetor is connected. Fig. 3 illustrates, in a diagrammatic way, the connection between the automatic speed regulator shown in Fig. 2, and the controlling part of the carburetor shown in Fig. 1. Fig. 4 is a fragmentary sectional view similar to Fig. 1, showing a change in the relative arrangement of the throttle and the outlet auxiliary valves.

The carburetor 1 is provided with the usual fuel outlet or nozzle 2 located in a suitable air passageway 3 that communicates with the intake manifold of the engine, in the manner well known in the art. The carburetor is provided with a suitable adjustable pin valve 4 for regulating the effective area of the outlet for the gasoline. It also has the usual throttle valve 5 that is manually operated, as by a lever 6, or other suitable means. The throttle 5 may be operated with a hand lever or accelerator pedal, in the manner well known in the art, to vary the supply of fuel to the engine and, consequently, to vary the speed of the engine or to suit the load.

The passageway 3 is provided with a pair of butterfly valves 10 and 11 located at opposite sides of the nozzle 2 and adjustably secured to the pins 12 which are rotatably supported in the wall of the carburetor. The valves 10 and 11 are operated by means of the arms 13 that are connected to the pins 12. The arms 13 are connected together by means of the link 14. Thus the arms 13 are moved together to move the valves 10 and 11 together. The valves 10 and 11 may be located in parallel relation or one may be located in slightly advanced position relative to the other to vary the vacuous condition created in the part of the passageway in which the nozzle 2 is located and vary the restriction to the air flow into that part of the passageway. The valves 10 and 11 are secured in their adjusted positions to the pins 12 by means of the clamping parts 15 or by any suitable screw or other clamping member.

The fuel nozzle 2 of the carburetor is located in the passageway 3 between the valves

100

10 and 11 and the throttle valve 5 is located intermediate the valve 10 and the fuel outlet 2 of the carburetor. The valve 11 is located in the air inlet side of the passage 16 of the carburetor, while the valve 10 is located in the fuel mixture outlet side 17 of the carburetor.

The valves 10 and 11 are automatically operated according to the speed of the engine by a suitable centrifugally operated mechanism that is elastically resisted in its movements to cause its operations to be produced substantially in proportion to the speed of the engine. Any suitable centrifugally operated means may be used for controlling the valves 10 and 11. The speed controlling device is connected to one of the shafts of the engine, such as to the cam shaft, to produce movement of the valves 10 and 11 and changes in area of opening in proportion to the changes in speed of the engine. In the form of construction shown, a governor mechanism 19, of a suitable type, is connected by means of the link 30 and the bell-crank 25 lever 21. The governor mechanism is provided with the usual fixed collar 22 and the movable collar 23 located on the shaft 24, which is connected by the usual slip collar connection with the bell crank lever 21. The shaft 24 is driven by the cam shaft 25 to which it is connected by means of the gear wheels 26. The weights 27 of the governor are connected to the collars by the links 28 and the movement of the collar 23, induced by the weights 27, is increasingly resisted by the spring 29 located intermediate the collars. Thus, the valves 10 and 11 will be operated to vary the manifold resistance according to the engine speed and also to control the pressure around the nozzle to give the proper ratio of air and gasoline for all operating conditions of the engine.

In the operation of my device, let it be presumed that the engine is running slowly, in which case the main control throttle 5 is only partly open and the auxiliary valves 10 and 11 are in their normal partially closed position, the speed of the engine not being sufficient to effect the operation of the governor. This normal partially closed position of the auxiliary valves, for example, may be considered as substantially that shown in Fig. 1. A sudden opening of the throttle valve 5, which is usually effected when a sudden accelerated speed is desired, will not effect a sudden corresponding opening of the carburetor passageway to the engine, inasmuch as the auxiliary valves 10 and 11, which are disposed on opposite sides of the fuel nozzle 2, remain in their partially closed position until the engine has acquired a speed sufficient to open such auxiliary valves through an operation of the governor. It is thus apparent that the usual knocking, occasioned by the sudden overcharging of the engine

as the throttle valve is suddenly opened, will be prevented due to the auxiliary valves opening gradually as the speed of the engine increases and thereby controlling the charge entering the cylinders. My device is also effective in preventing overcharging and consequent knocking of the engine when operating under a heavy load at low speed, in which case the throttle 5 is usually in wide open or fairly wide open position. In this case, until the engine has acquired sufficient speed to act on the auxiliary valves 10 and 11 through the governor, the inrush of air through the manifold to the cylinders, which would otherwise be permitted when the throttle 5 is wide open, will be prevented. Furthermore, a more uniform condition is provided at all times in the manifold around the fuel nozzle irrespective of the extent of opening of the valve 5.

Overcharging of the engine upon a sudden opening of the throttle valve may be prevented by the use of a single auxiliary valve between the carburetor and the engine. It is more desirable, however, to provide the two auxiliary valves 10 and 11, one on each side of the carburetor, so that under all conditions the proper degree of vacuum may be maintained in the region of the nozzle 2 and a fuel mixture of the proper proportions will be insured.

I also wish it understood that it is not important so far as the operation of the invention is concerned whether the throttle valve 5 is between the auxiliary valve 10 and the fuel nozzle or on the opposite side of such auxiliary to the fuel nozzle. This arrangement is shown in Fig. 4, in which the throttle valve is designated 5^a and the auxiliary valve 10^a. If desired, the auxiliary valve or valves, as the case may be, may be manually controlled, but such a control is not as satisfactory as an automatic control wherein the action of the auxiliary valves is responsive to the varying speeds of the engine.

I wish it understood that my invention is not limited to any specific construction, arrangement or form of parts, as it is capable of numerous modifications and changes without departing from the spirit of the claims.

Having thus described my invention, what I claim as new and desire to secure by U. S. Letters Patent is:

1. In a carburetor for an internal combustion engine, the carburetor having a passageway communicating at one end with the intake of the engine, the carburetor having a fuel inlet communicating with the passageway and an air inlet for said passageway on the side of the fuel inlet opposite to the point of connection of the carburetor with the intake of the engine, a valve for closing the said passageway and interposed between the air inlet and the fuel inlet, a second valve for closing the passageway interposed between

the fuel inlet and the intake of the engine, a throttle valve for closing the passageway and interposed between the fuel inlet and the second named valve, means for automatically 5 operating the first and second named valves according to the speed of the engine, and means for manually operating the throttle valve.

2. In a carburetor for an internal combustion engine, an intake passageway leading to the engine, a gasoline inlet to said passageway, a throttle valve in the passageway, and two auxiliary valves at opposite sides of the gasoline inlet operable independently of the 10 throttle valve to control the admission of fuel mixture to the engine to prevent the engine from overcharging upon a sudden opening of the throttle valve at low speeds.

3. In combination with an internal combustion engine, an intake passageway for the engine, a carburetor having a fuel nozzle opening into said passageway, a throttle valve in said passageway, auxiliary valves disposed in said passageway at opposite 20 sides of the fuel nozzle and connected to operate in unison and normally standing in partially open position when the engine is running at low speed, and speed controlled means automatically operable to increase the 25 opening of the auxiliary valves upon a predetermined increase in the speed of the engine.

4. In combination with an internal combustion engine, an intake passageway therefor, a carburetor associated with said passageway and having a fuel nozzle opening thereinto, a throttle valve in said passageway, auxiliary valves in said passageway operable independently of the throttle valve 30 and normally standing at predetermined partially open positions, and means including a governor actuated by a running of the engine to begin to open the auxiliary valves when the engine has acquired a predetermined speed and to increase such opening 35 with the increase of the engine speed.

5. In combination with an internal combustion engine, an intake passageway for the engine, a fuel inlet for said passageway, a 40 throttle valve in said passageway, a pair of auxiliary valves disposed in said passageway, one at each side of the fuel inlet, and means connecting said auxiliary valves for simultaneous operation to partially close said 45 passageway at both sides of the fuel inlet or to increase the opening thereof according to the speed of the engine.

In testimony whereof I have hereunto signed my name to this specification.

60 MARION MALLORY.
